UNITED STATES PATENT OFFICE.

FRANÇOIS ROCHEFORT, OF PARIS, FRANCE.

FUEL ATOMIZER AND VAPORIZER.

Application filed March 25, 1922. Serial No. 546,911.

To all whom it may concern:

Be it known that FRANÇOIS ROCHEFORT, citizen of the French Republic, residing 81 Rue Blomet, Paris, France, has invented 5 certain new and useful Improvements in Fuel Atomizers and Vaporizers, of which the following is a specification.

My invention relates to liquid fuel atomizers and vaporizers. In the apparatus according to my invention, the liquid fuel is subjected to several successive actions, viz:

1° Forced feeding under high pressure and mingling of the fuel at a predetermined temperature.

15 2° Atomization.

3° Vaporization and diffusion under the mechanical action of a compressed and expanded gas suited to the nature of the liquid to be vaporized.

20 4° Ignition, when applied to combustion apparatus.

The accompanying drawing, for purposes of illustration, shows an embodiment of my apparatus in combination with an igniting device, intended for supplying liquid fuel directly to an internal combustion engine.

The apparatus comprises a cylinder 1 containing a movable piston-valve 2. This fluid-tight piston is hollow in order to have 30 a very low inertia and terminates at one end in a valve 3 the movement of which, in direct relation to the movement of the piston valve, is limited by an abutment.

The fuel to be vaporized is forced under 35 high pressure into the cylinder 1, through the port 4.

The compressed gas used to effect the vaporization is introduced at 5 and, together with the spring 6, causes the return of the 40 piston-valve 2 and the closing of the valve 3.

A port 7 normally closed by the piston valve 2 is connected to a pipe 8 leading the fuel to the injector 9 where it enters grooves 10 of increasing cross-section, straight or helicoidal according to the applications, and which are provided in the periphery of, and extend lengthwise along, a mass of non-oxidizable metal, constituting the heater 11 located within the injector body 9 which is 45 at its end provided with a multiple-jet nozzle 12. Its main jet aperture 15 forms an extension of the central feed channel 13.

Fine grooves are provided in the injector body 9 so as to constitute a series of secondary jets, gauged and fed by means of obliquely extending conduits opening out into 50

an annular groove which forms a communication between all the grooves 14.

A casing 16 enclosing the injector-body 9 forms around same an annular chamber 17 60 of increasing cross-section.

A check valve 18 establishes at the required moment a communication between the chamber 17 and the supply of compressed gas at 5. A small automatic ball-valve 19 65 allows communication with the atmosphere at the required moment through the port 20.

The casing 16 ends in a series of discharge openings 21 constituted by the nozzle 12, the 70 casing itself and the body of the igniting device 22 opening out into the cylinder 30 of the engine.

The feeding of the first discharge opening occurs through the helicoidal recesses 23 75 provided in the body of the nozzle 12, and that of the second discharge opening occurs through the annular chamber 24 formed by bores in the wall of the casing 16 and opening out into the chamber 17. In some cases, 80 a hollow heat-conducting metal sphere 25 brought to the temperature of ignition of the fuel before starting, forms a temperature regulator for the casing 16 and the injector 9. 85

The inside of this sphere 25, which is in contact with the gases during their combustion, may carry blades or wings 26 to increase the radiation surface; its purpose is to regulate the temperature of the above-mentioned elements. The part 22 which is a bad conductor, effects the ignition. Aper- 90 tures 27 are provided to secure the formation of a carburetted zone in front of the igniting device. 95

Conduits 28 provided in the casing 16 allow communication between the chamber 17 and the inside of the sphere 25.

A coiled spring 29 constitutes a compensator for the expansion of the heater 11, 100 which is able to move within the body 16 of the injector.

The element 11 is heated by conduction, being in contact through its longitudinal projections forming the grooves 10 with the 105 injector 9, which in turn is in contact with the casing 16. The latter receives its heat from the metal sphere 25.

The operation of the apparatus is as follows:

The liquid fuel, fed under high pressure by means of a pump, enters through the 110

port 4. Being non-compressible, it pushes before it the piston valve 2 which controls the opening of the air admission valve 3 and uncovers the port 7 through which the liquid fuel, by way of the pipe 8, reaches the expansion grooves 10 around the heater 11, whereby the temperature of the fuel is raised. The fuel is thoroughly mingled and expelled through the conical jet apertures 14 and 15, of small cross-section, so as to allow the expansion of the fuel which, owing to its gyratory motion, and its fluidity, leaves the jet apertures completely atomized.

At the moment when the fuel is introduced 15 under pressure and the valve 3 is opened thereby, compressed air under high pressure enters through the port 5 and opening check valve 18 flows into the annular chamber 17 of increasing section. The air is heated by 20 the walls of the casing 16 and while passing, carries away with it the atomized liquid escaping from the inclined jet apertures 14 around the channel 13.

This compressed air passes through the 25 helicoidal grooves 23 provided in the body of the nozzle 12 carrying away with it the atomized fuel escaping through the central jet aperture 15 a jet of compressed air also coming from the annular chamber 24. The 30 resulting vaporized mixture, escaping at 21 at high velocity, causes a suction, through the apertures 27, of compressed air into the engine cylinder, thus facilitating the diffusion of the mixture in the mass. Consequently, the ignition is more rapid, being 35 made easier by the creation of the agitation and the whirlwind-like currents around the igniting device 22.

During the feeding of the fuel, a certain 40 quantity of air passes through the conduits 28 in order to renew the supply of gases within the sphere 25, which constitutes a temperature-regulating device, in that this sphere being heated by the gases of combustion yields a certain amount of its heat to the feeding device.

As the injection is completed, the hydraulic pressure ceases and the compressed air 45 exerting a strong pressure on the upper portion of the valve 3 closes the same at the same time returning the piston-valve 2 to its initial position. The port 7 is now again closed until the next injection. During the closing movement of the piston-valve 2 the 55 compressed air still penetrates into the annular chamber 17 and by its expansion completely carries away all the fuel in order to avoid the formation of a carbonaceous clogging at the end of the injector. The 60 automatic ball-valve 19 allows the admission of pure air to expel the burnt gases contained in the chamber 17 when the driving piston is at the admission stage. The circulation and the expansion of the cold air 65 through the annular chamber 17 make it

possible to control the temperature of the injector-body 9, the expanded air absorbing off a certain quantity of heat in order to avoid the condensation of the fuel during vaporization.

The drawing illustrates one embodiment of my invention, but it is quite obvious that the arrangement of the elements composing the pulverizer may vary without the mode of operation being changed.

The device also may have other uses than that indicated.

I claim as my invention:

1. A liquid fuel atomizer and vaporizer comprising a central heating body, an injector casing enclosing said heating body and being spaced therefrom, an injector nozzle at the end of the said casing, an outer casing surrounding the said injector casing and forming therewith an annular chamber, a cylinder in communication with the said injector casing, a piston valve movable in the said cylinder and adapted to be operated by the pressure of the liquid fuel to admit the same to the said injector casing, and an air-inlet valve moving with the said piston-valve, so as to admit proportionally to the amount of fuel injected into said injector casing compressed air into the said annular chamber, the compressed air forming a mixture with the heated atomized fuel in the said injector nozzle and carrying the fuel along with it.

2. The combination as set forth in claim 1, comprising also a spring-controlled check valve interposed between the said air-inlet valve and the said annular chamber.

3. The combination of the fuel atomizer and vaporizer as set forth in claim 1 with an internal combustion engine, the said combination comprising also a hollow spherical body arranged around the said outer casing in communication with the engine cylinder, so as to be heated by the hot combustion gases.

4. The combination of the fuel atomizer and vaporizer as set forth in claim 1 with an internal combustion engine, the said combination comprising also a hollow spherical body arranged around the said outer casing in communication with the engine cylinder, so as to be heated by the hot combustion gases, and heat absorbing and conducting blades provided in said hollow spherical body.

5. A combined liquid fuel atomizer and vaporizer comprising a central heating body for the fuel containing grooves so as to impart a gyrating motion to the fuel, an injector casing enclosing the said heating body being spaced therefrom, an injector nozzle at the end of said casing and having axial and radial apertures, an outer casing surrounding the said injector casing forming therewith an annular chamber, a cylinder in

- communication with said injector casing, a piston-valve movable in said cylinder and adapted to be operated by the pressure of the liquid fuel, thereby admitting the same to the said injector casing, an air-inlet valve moving with the said piston valve so as to admit compressed air to the said annular chamber in proportion to the amount of fuel injected into the said injector casing, the compressed air forming a mixture with the heated atomized fuel in the said injector nozzle, and a spring-controlled check valve interposed between the said air-inlet valve and the said annular chamber.
5. The combination as set forth in claim 1, comprising also an automatic ball-valve so arranged as to periodically admit pure air to the said annular chamber.
10. In testimony whereof I affix my signature.

FRANCOIS ROCHEFORT.
